UNITED STATES PATENT OFFICE.

MILTON A. HIRSH, OF LOS ANGELES, CALIFORNIA, ASSIGNOR TO COHN, GOLDWATER COMPANY, OF LOS ANGELES, CALIFORNIA, A CORPORATION OF CALIFORNIA.

DESIGN FOR A CHILD'S DRESS.

55,860.

Specification for Design.

Patented July 20, 1920.

Application filed April 14, 1919. Serial No. 290,093. Term of patent 3½ years.

To all whom it may concern:

Be it known that I, MILTON A. HIRSH, a citizen of the United States, residing at Los Angeles, in the county of Los Angeles and State of California, have invented a new, original, and ornamental Design for a Child's Dress, of which the following is a specification, reference being had to the accompanying drawing, forming part thereof.

Fig. 2 is a rear view of the same.

I claim:

The ornamental design for a child's dress, as shown.

MILTON A. HIRSH.

Witnesses:

A. C. LARKIN,
EDMUND A. STRAUSE.
